HORACE D. JERMON, OF GLOUCESTER, NEW JERSEY, ASSIGNOR TO CRESCENT APPLIANCE CORPORATION, OF GLOUCESTER, NEW JERSEY, A CORPORATION OF NEW JERSEY.

ELECTRIC HEATER.

Application filed June 1, 1928. Serial No. 282,062.

This invention relates to improvements in electric heaters for heating the rooms of buildings and for other purposes.

An object of the invention is to provide a novel, inexpensive and efficient means for supporting an electrical resistance element or bar within or forwardly of a suitable reflector and for permitting electrical current to be supplied thereto.

10 A further object of the invention is to so construct and arrange the parts that a dome shaped reflector may be employed and that the resistance element may be supported by arms extending forwardly and diverging 15 outwardly from a single insulating block which is secured to the central portion of the reflector.

With the foregoing and related objects in view the invention consists of the elements 20 and the combinations of them hereinafter described and claimed.

In the accompanying drawings, illustrating the invention,

Figure 1 is a side view of an electric heater 25 embodying my invention.

Figure 2 is a front view thereof.

Figure 3 is a horizontal section through the heater, on line 3—3 of Fig. 2.

Figure 4 is a vertical section on line 4—4 30 of Fig. 2.

Referring to the drawings, 2 designates a reflector and 5 a supporting base or stand therefor.

The reflector comprises dome shaped front 35 and rear metal plates 6 and 7, respectively. The plates 6 and 7 are provided with outwardly extending, annular flanges 8 and 9, respectively, and the flange 8 is bent or formed around the flange 9, as shown in Fig. 3, to secure the surrounding edge portions of the plates 6 and 7 together and hold the central portions thereof spaced from each other.

45 The outer or rear plate 7 is provided with openings 10 suitably spaced around the forward portion thereof for the circulation of air through the space between the plates 6 and 7 to keep them cool.

50 The lower rearward portion of the re-

flector 2 is provided with a bracket 11 which is secured to the rear plate 7 and pivotally connected to the upper portion of the base 5 by means of a bolt 12 which is provided with a suitable thumb nut 13 by means of 55 which the reflector may be clamped in different positions of adjustment on the base 5.

The upper portion of the reflector 2 has a fixed post 14 thereon carrying a ring or handle 15 which is pivoted thereto for 60 the purpose of carrying the heater from place to place.

Located centrally within the reflector 2 is a block 16 which is formed of suitable electrical insulating material. The block 16 65 comprises a horizontally extending front portion 17 and a central portion 18 which extends rearwardly from the front portion 17, as clearly shown in Fig. 3.

The front portion 17 of the block 16 is 70 located within and fitted to an opening 19 in the front reflector plate 6 and the front portion of the block extends forwardly of the front plate and it is provided with laterally or outwardly extending parts which 75 engage the forward surface of the front plate 6 around the opening 19 therein.

The central portion 18 of the block 16 extends to and engages the forward surface of the rear plate 7, and the block 16 is secured 80 in place by a screw 20 which extends through the plate 7 and is screwed into the block 16. The head of the screw 20 engages the rearward surface of the rear plate 7 and draws the block 16 against the forward surfaces 85 of the plates 6 and 7 and thereby holds the block firmly in place within the central portion of the reflector with the horizontally extending front portion 17 of the block 90 spaced forwardly from the rear plate 7.

The front wall of the block 16 is provided with a horizontally extending groove 21 for the laterally spaced rearward end portions of flat arms 22 which are formed of 95 spring metal and which extend forwardly and diverge outwardly from the respective sides of the block 16, as shown in Fig. 3.

Directly back of the rearward end portions of the arms 22 are the terminal plates 100

23 of flexible electrical conducting wires 24. The plates 23 are fitted against the rearward surfaces of the respective sides of the forward portion 17 of the block 16, and the 5 arms 22 and plates 23 are secured to the block 16 by suitable bolts 25 which extend through them and clamp them together. The bolts 25 are formed of metal and serve as a common means for electrically connecting 10 the wires 24 and arms 22 and for securing them to the block 16.

The wires 24 are covered with insulation and they extend out through an opening 26 in the rear plate 7 above the block 16, and 15 the wires 24 are protected from the plate 7 by a ring of insulating material 27 which is set in the opening 26, as shown in Fig. 4.

The engagement of the block 16 with the wall of the opening 19 in the plate 6 prevents 20 the accidental turning of the block about the axis of the screw 20, and the engagement of the upper and lower edges of the adjacent ends of the arms 22 with the adjacent walls of the groove 21 prevents the 25 arms 22 from accidentally turning about the axes of the bolts 25.

The arms 22 diverge from the block 16 in 30 spaced relation to the front reflector plate 6 and their free forward ends are bent to extend parallel to each other in opposing relative positions and they are provided with re-enforcing plates 28 which are riveted thereto, as shown in Fig. 3.

The opposing walls of the re-enforced, 35 parallel ends of the arms 22 have sockets 29 formed therein for the reception of the ends of a bar or rod 30 which may be formed of any suitable electrical resistance material which will be heated to a high degree when 40 electric current is supplied thereto. Normally, when the bar 30 is removed from the arms 22, the socketed free ends of the arms are somewhat closer together than as shown in the drawings so that, after they have 45 been sprung apart to permit the insertion of the ends of the bar 30 into the sockets 29, they will exert inward pressure against the ends of the bar and hold it in place clamped between and in electrical contact with the 50 ends of the arms 22.

It will now be understood that when the wires 24 are connected to a source of electric current the bar 30 will be heated in the 55 manner common to electric heaters of the class to which my invention relates.

The wires 24 may be of any desired length and they may be provided with any convenient means enabling them to be connected to and disconnected from the current supplying conductors of a building in the usual well known manner.

The resistance bar 30 which I have used with very good results is formed of carborundum. Such bars are now in open 60 sale

upon the market under the name "Globar" sold by Globar Corporation of Niagara Falls, New York, but other suitable resistance bars can be used without departing from my invention.

70

I claim:

1. In an electric heater, a reflector comprising front and rear plates having their edge portions connected and having their central portions spaced from each other, a 75 block of electrical insulating material secured to the central portion of the rear plate and extending through the central portion of the front plate to a position forwardly of the forward surface thereof, spaced arms extending forwardly and diverging outwardly from said block and being formed of electrical conducting material, an electrical resistance bar connecting the forward end portions of the arms, flexible electrical conductors extending from said block, and bolts 80 extending through said block and electrically connecting said arms and said conductors and securing them to the block.

2. In an electric heater, a reflector comprising front and rear plates having their edge portions connected and having their central portions spaced from each other, a 85 block of electrical insulating material secured to the central portion of the rear plate and extending through the central portion of the front plate to a position forwardly of the forward surface thereof, spaced arms 90 extending forwardly and diverging outwardly from said block and being formed of electrical conducting material, an electrical resistance bar connecting the forward end portions of the arms, flexible electrical conductors extending from said block, and bolts 95 extending through said block and electrically connecting said arms and said conductors and securing them to the block, said arms and said block having co-engaging parts preventing the turning of the arms about the 100 axes of the bolts.

3. In an electric heater, a reflector comprising front and rear plates having their edge portions connected and having their central portions spaced from each other, a 105 block of electrical insulating material ex-

tending from the central portion of the rear plate to and through the central portion of the front plate to a position forwardly of the forward surface thereof, spaced arms extending forwardly and diverging outwardly 110 from said block and being formed of electrical conducting material, an electrical resistance bar connecting the forward end portions of the arms, flexible electrical conductors extending from said block and electrically connected 115 to said arms, and a centrally arranged screw extending through the rear plate of the reflector and into said block and connecting them together, said front plate and said block having co-engaging parts preventing the turn- 120

ing of the block about the axis of the screw.

4. In an electric heater, a reflector comprising front and rear plates having their edge portions connected and having their central portions spaced from each other, the front plate having a central opening therein, a block of electrical insulating material having a horizontally extending front portion within the opening in the front plate and 5 spaced from the rear plate, said block having a central portion extending rearwardly from the front portion thereof to the rear plate, means to secure the central portion of the block to the rear plate, spaced arms extending forwardly and diverging outwardly 10 from the respective sides of the front portion of the block and being formed of electrical conducting material, an electrical resistance bar connecting the forward end portions of the arms, flexible electrical conductors extending from the back of the respective sides of the front portion of the block, and bolts extending through the respective sides of the front portion of the block and 15 electrically connecting said arms and said conductors and securing them to the block.

5. In an electric heater, a reflector comprising front and rear plates having their edge portions connected and having their central portions spaced from each other, the front plate having a central opening therein, a block of electrical insulating material having a horizontally extending front portion within the opening in the front plate 20 and provided with a horizontally extending groove in the front wall thereof, said block having a central portion extending rearwardly from the front portion thereof to the rear plate, means to secure the central portion of the block to the rear plate, arms having adjacent spaced end portions seated in said groove, said arms extending forwardly and diverging outwardly from the respective sides of the front portion of the block and 25 being formed of electrical conducting material, flexible electrical conductors extending from the back of the respective sides of the front portion of the block, and bolts extending through the respective sides of the front 30 portion of the block and electrically connecting said arms and said conductors and securing them to the block.

6. In an electric heater, a reflector comprising front and rear plates having their edge portions connected and having their central portions spaced from each other, the front plate having a central opening therein, a block of electrical insulating material engaging the central portion of the forward 35 surface of the rear plate and extending therefrom to and through the opening in the front plate and having laterally extending parts engaging the forward surface of the front plate, a screw engaged with the rear plate 40 and screwed into and holding said block

against the forward surfaces of said plates, spaced arms extending forwardly and diverging outwardly from said block and being formed of electrical conducting material, an electrical resistance bar connecting the forward end portions of the arms, and flexible electrical conductors extending from said block and electrically connected to said arms. 45

In testimony whereof I affix my signature.
